UNITED STATES PATENT OFFICE.

JAMES ALLAN, OF GLASGOW, SCOTLAND.

SELF-FEEDING PAINT-BRUSH.

1,085,234.

Specification of Letters Patent.

Patented Jan. 27, 1914.

Application filed January 27, 1909. Serial No. 474,575.

To all whom it may concern:

Be it known that I, JAMES ALLAN, a citizen of the United Kingdom of Great Britain and Ireland, and resident of 159 Paisley 5 road west, Glasgow, Scotland, painter, have invented certain new and useful Improvements in and Relating to Self-Feeding Paint-Brushes, of which the following is a specification.

10 This invention relates to improvements in and relating to self feeding paint brushes and has for its object to more effectually effect the distribution of the paint on the article to be painted and also to prevent any 15 loss of paint and to obtain a better and more uniform surface thereof.

With my improved brush, a great saving of time is effected, thereby greatly reducing the cost.

20 Figure 1 shows a general view of the brush, tank and connections. Fig. 2 a view of the lower portion of the tank at right angles to the tank shown in Fig. 1. Fig. 3 an enlarged sectional elevation of the brush. Fig. 4 an enlarged sectional elevation of the top part of Fig. 3, viz. the stock and showing the manner of attaching the bristles to the top of the stock. Figs. 5 and 25 6 are modifications, hereinafter referred to.

30 The paint to be used is placed in the tank A which paint is discharged into the supply pipe B communicating with the brush C at any suitable pressure. Also communicating with the brush C and the top of the tank 35 A is the air supply pipe D; the air and paint from the said tank passing up separate channels in the stock of the brush C and meeting near the outlet of the nozzle c of the brush, as hereinafter more particularly 40 described.

The brush consists of a metal or other stock having preferably two channels a and d; the paint supply pipe B and air supply pipe D communicating with the channels a 45 and d, respectively. The said channels preferably lead from the bottom end of the stock of the brush C, to the tube b which may be secured or formed in the top end of the stock of the brush. In the case of the air 50 supply channel d, I prefer that it be conducted upwardly into the tube b, and I may effect this by means of the small pipe d' screwed into the channel d of the air supply. The open end of the pipe b is provided with 55 a cap b' which has a pair of outlet ducts or

ports b² permitting the issuance of liquid or fluid from the pipe b to the atmosphere. The openings of these ports on the interior face of the cap b' are spaced apart, while the intermediate portions thereof tend to converge so that the opening on the outer face of the cap b' is common to both ports. 60

The paint supply and air supply to the interior of the cavity b³ is governed or controlled by the ordinary rotatable one way 65 valves a¹, d², placed in the channels a and d—preferably in the position shown. In the arrangement shown it will be observed that the air from the pipe d² does not really come into contact with the paint supply 70 from the pipe a until the paint is near the top of the cavity b³, then however it impinges on the paint and splits it up or atomizes it; the paint passing out of the holes b² of the cap b' in the form of very fine 75 spray—along with the air from the pipe d.

By so splitting up the paint in the manner set forth, the paint becomes thoroughly atomized—the particles having no tendency to unite until sprayed on to the work. 80

In my preferred construction the cap or nozzle b' is surrounded by a suitable set of bristles 1 which are secured to the outer face of the socket or sleeve c'. These bristles extend beyond the nozzle b' and form a path- 85 way, as it were, for the stream of liquid issuing from the said nozzle.

Referring to Fig. 3 there are shown bristles 1 extending upward and beyond the cap b'; these bristles entirely surround the said cap, 90 forming an ellipse in plan view.

Fig. 4 discloses the series of bristles in side elevation, the free edges thereof in this instance being serrated as at 2.

As is well known in the application of paint by, or under pressure, it is practically impossible to so regulate the flow thereof that just the exact amount of paint desired will be forced from the nozzle. Whenever the flow of paint is too great, the surplus there- 95 of forms what may be termed "runners," which if not taken up in some manner, will result in the work being streaked. To obviate this difficulty, I have, as above stated provided an absorbent member consisting of 100 bristles or hair, which is secured to and extends beyond the end of the nozzle. It must be understood that the bristles do not enter into or obstruct the path of the liquid which issues from the nozzle, but that they simply 105 110

surround the end of the nozzle, and form, as it were, an extended passageway for the liquid.

From the above it will be seen that the absorbent member is not used to apply the paint on the work, but that it is used primarily to take up or absorb any surplus paint which issues from the nozzle.

The socket c' may be secured to the stock 10 of the brush after the manner as shown in Fig. 4 that is to say by means of the set screws c^2 which are inserted through each end of the socket c' and thence into the top ends of the stock.

15 The bristles or hair of the brush may be arranged perpendicularly or be angled to or from the center of the cap or nozzle b^1 , but I prefer that they be angled outward as shown in Fig. 3.

20 In the brush portion of the general view Fig. 1 I have shown the valves a^1 , d^2 with their actuating handles a^2 , d^3 in what I consider the best position for controlling the paint and air supply when using the brush, 25 but they may be otherwise arranged.

In some cases I may deem it advisable to crank or angle the stock of the brush, as shown in Fig. 5.

30 I may also employ in lieu of the cap b^1 , the cap b^4 , Fig. 6 which screws on the outside of the pipe b and which cap b^4 may have its underside cone-shaped as shown.

35 In the sectional elevation of the brush Fig. 3 it will be observed that a brush or wire for cleaning purposes may be passed right through the paint supply channel a and that by removing the small set screw d^4 at the bottom of the air channel d , similarly a cleaner may be passed right through it 40 and the pipe d^1 .

As is obvious the parts such as b and b^1 may readily be dismantled and cleaned.

45 The tank A for holding the supply of paint may be of an ordinary nature that is to say it may have the double bend pipe arrangement shown; one pipe communicating with the air supply pipe d and the other pipe communicating with a pressure pump (hand or otherwise) for filling the tank A 50 with air.

The air supply pipe to tank and air supply pipe to the pipe d may each be provided with shut off valves such as E and F as also may the paint supply pipe be provided with the 55 valve G Fig. 2.

The tank is preferably provided with a filler such as H which may have a check valve, to allow the paint to run into the tank but to prevent the escape of air from it.

60 Also the tank may have an indicator such

as J for indicating the amount of air pressure in the tank.

The tank A is preferably half filled with paint and the bottom is preferably made as shown in Fig. 2.

65 Although I have referred to a tank such as A, any convenient form of tank in which an air pressure is exerted may be employed.

I have also referred herein to the brush using paint, but it may equally well be used 70 for white or color washes and patent washer such as Hall's distemper, Durisco and the like.

The brush may in some cases be used as a sprayer that is to say without the bristles or hair and when in this form it may be used 75 for other purposes such as spraying disinfectant or it may be used with water for washing carriages and such like.

I have shown only one paint brush being 80 fed from the tank A, but a similar tank may be employed to feed any number of brushes.

Claims:

1. In self feeding paint brushes, a paint spraying nozzle having converging outlets 85 opening into a common chamber and having separate air and fluid supply pipes, in combination with bristles or hairs surrounding the free end of the said nozzle and adapted to take up any surplus fluid sprayed out by 90 the nozzle, substantially as described.

2. In self feeding paint brushes, the combination with a receptacle to receive liquid under pressure, of a spraying nozzle having a liquid channel and a fluid channel opening 95 into a common chamber, a pair of converging outlets from said nozzle, and having bristles or hairs surrounding said nozzle adapted to absorb any surplus liquid sprayed out by said nozzle, substantially as described. 100

3. In self feeding paint brushes, the combination with a spraying nozzle, of a ring, a series of bristles or hairs secured thereto and extending beyond the free end of said nozzle, said ring being detachably secured to 105 said nozzle, substantially as described.

4. A painting apparatus comprising a paint spraying nozzle adapted to direct paint against a surface to be painted and a paint absorbing material surrounding and extending beyond the spray, permitting free passage of the paint in the direction of the discharge of the spray but restricting lateral expansion of the paint issuing from the spray nozzle. 110
